UNITED STATES PATENT OFFICE

133,227

DESIGN FOR A CHIME SIGNAL

Edward J. Dourson, Greene Township, Hamilton
County, Ohio

Application September 30, 1941, Serial No. 103,575

Term of patent 7 years

To all whom it may concern:

Be it known that I, Edward J. Dourson, a citizen of the United States and a resident of Greene Township, in the county of Hamilton and State of Ohio, have invented a new, original, and ornamental Design for a Chime Signal, of which the following is a specification, reference being had to the accompanying drawing, forming part thereof, in which—

Figure 1 is a front elevational view of a chime signal, showing my new design;

Fig. 2 is a top plan view of the same, on a somewhat larger scale;

Fig. 3 is a bottom plan view of the same, on said larger scale;

Fig. 4 is a side elevational view of the same, on said larger scale, lower portions being omitted for lack of space; and

Fig. 5 is a front elevational view like Fig. 1, but on a further enlarged scale, lower portions being omitted for lack of space.

I claim:

The ornamental design for a chime signal, as shown.

EDWARD J. DOURSON.
